CLAIM

The ornamental design for a molded meat product or
similar article, as shown and described.

DESCRIPTION

FIG. 1 is a top plan view of the molded meat product or
similar article showing my new design;

FIG. 2 is a bottom plan view thereof;

FIG. 3 is a front elevational view thereof;

FIG. 4 is a rear elevational view thereof;

FIG. 5 is an end elevational view thereof; and

FIG. 6 is an end elevational view of the end opposite
that shown in FIG. 5.
